UNITED STATES PATENT OFFICE.

CHARLES D. BONSALL, OF PARNASSUS, PENNSYLVANIA, ASSIGNOR TO P. H. MURPHY COMPANY, OF PARNASSUS, PENNSYLVANIA, A CORPORATION OF PENNSYLVANIA.

CARLINE BRACKET.

Application filed September 19, 1921. Serial No. 501,696.

To all whom it may concern:

Be it known that I, CHARLES D. BONSALL, a citizen of the United States, residing at Parnassus, in the county of Westmoreland and State of Pennsylvania, have invented a new and useful Improvement of Carline Brackets, of which the following is a specification.

This invention relates to improvements in metal carlines of car roofs and more particularly to brackets for supporting the ends of the carlines upon the side plates of the car.

When it is desirable to support the roof upon angle carlines and have the roof sheets rest upon the side plates, it is necessary to terminate the ends of the carlines short of the side plates and provide them with brackets which not only engage the side plates but also the underside of the carlines.

It is an object of this invention to form a bracket of this character which will embrace the top of the side plate and engage one side and support the bottom of a carline constructed from a commercial shape of angle iron.

While the preferred form of this invention is illustrated upon the accompanying sheet of drawing, yet it is to be understood that minor detail changes may be made without departing from the scope thereof.

In the drawings:

Figure 1 is a top plan view, with parts broken away, of an angle iron carline supported by this improved bracket in place upon the side plate of a car.

Figure 2 is a view in side elevation of Figure 1.

Figure 3 is a top plan view of a pair of brackets as formed from a plate of metal, before severance, with the outline of the plate indicated by dotted line.

Figure 4 is a view in end elevation of Figure 3.

To obtain the greatest strength and rigidity in a carline constructed of commercial angle iron, one flange should be vertical and the other horizontal, with the horizontal flange attached to the side plate by a bracket which also forms an additional strengthening means for the vertical flange to resist twisting movements out of the vertical as occurs from the weaving of the car when it is in motion.

In accordance with this invention each

pair of brackets for supporting the opposite ends of a carline of this type are pressed from a rectangular plate of metal, are similar with the supports for the vertical flange oppositely disposed, as is necessary as shown in Fig. 1, and are formed without any excess metal to be trimmed off. This improved method of forming the brackets comprises the pressing of rectangular sheets of metal of the necessary thickness to give the desired strength. The sheets are of twice the width of a single bracket and approximately of the same length as the overall length of a single bracket. The method includes the pressing down of a flange along the width of the plate on one edge and the pressing down in the same direction of a rectangular portion from the opposite edge, which depression is symmetrical with respect to the center line at right angles to that edge and extends inward towards the flanged edge until the distance from the flange and the depressed wall is such as to be able to embrace the side plate to be used on the car. In the pressing rectangular walls are formed on each side of the center line which draws in the metal of the body of the plate, as shown in Figures 3 and 4. The angles of the flange, parallel depressed walls and depressed body of the plate between these walls to the normal main body of the plate are regulated by dies to correspond to the top of the side plate to be embraced to support the carline end in proper position. The pressed sheet is then severed in half along its center line as indicated by line 5-5 on Figures 3 and 4, so that the operation of pressing and severing forms two complete brackets, one of each end of a single carline.

Each bracket thus formed comprises a main body 1 adapted to rest upon the top of the side plate 2 and be secured thereto, with the flange 3 depending on the exterior and engaging the outer surface of the side plate, with a depending wall 4 engaging the inner side of the side plate which wall continues inward at an angle to the side plate to form a supporting body 5 for the lower flange 6 of the carline, and having a vertical wall 7 extending upward integral with the body 5, wall 4 and main body 1 adapted to engage the side of the vertical flange 8 of the carline. As seen from Figures 3 and 4 the main body 1 which rests

upon the top of the side plate is approximately twice the width of the carline support 5 and is preferably secured to the side plate by two bolts 9 and 10 adjacent each 5 end, and as one end of the main body tapers into vertical wall 7, its shape and its engaging the outer side of the side plate by its down turned flange 3 with the vertical wall 7 in contact with the vertical flange 8 of the 10 carline and the horizontal flange 6 secured to the body 5 forms a bracket that not only anchors the end of the carline to the side plate, but also resists the twisting on the carline from the weaving of the car.

15. What I claim is:

1. A metal carline bracket having a main body adapted to embrace the top of a car side plate having an integral vertical portion adapted to engage the interior of the 20 side plate provided with integral inwardly extending horizontal and vertical projections adapted to support and engage the horizontal and vertical members of a carline, said main body being of greater width 25 than the width of the carline and bending from one end into the integral inwardly extending vertical portion.

2. A metal carline bracket having a main body adapted to embrace the top of a car side plate and integral inwardly extending horizontal and vertical projections adapted 30 to support and engage the horizontal and vertical members of a carline below the top of the side plate, said vertical projection as

it approaches the side plate bending away 35 from the carline into the portion of the main body adapted to rest on the top of the side plate.

3. A metal carline bracket having a main body adapted to embrace the top of a car side plate of greater width than the carline to be supported having the depending portion on the interior of the side plate provided at one end of the bracket with a horizontal inward projection adapted to support 40 and engage the horizontal portion of the carline and an intermediate vertical projection adapted to engage the vertical portion of the carline and departing therefrom adjacent the interior of the side plate to bend 45 into the main body for the rest of its extent.

4. A pressed metal carline bracket comprising a flat portion adapted to engage and rest upon the top of a car side plate for substantially twice the width of the carline 50 to be supported and engaged by the bracket and having a depending integral portion at one end adapted to engage the interior of said side plate extending into a horizontal projection adapted to support and engage 55 the horizontal portion of a carline and an intermediate vertical portion adapted to engage the vertical portion of said carline and integral with said horizontal, depending and flat portions with the top edge bending 60 into the end of the flat portion opposite the depending portion.

CHARLES D. BONSALL.
